UNITED STATES PATENT OFFICE.

MIECISLAS J. SZAMEIT, OF CHICAGO, ILLINOIS, ASSIGNOR OF ONE-HALF TO JOHN STELK, OF CHICAGO, ILLINOIS.

DESIGN FOR A BADGE OR EMBLEM.

51,427.

Specification for Design.

Patented Oct. 23, 1917.

Application filed May 15, 1917. Serial No. 168,895. Term of patent 3½ years.

To all whom it may concern:

Be it known that I, MIECISLAS J. SZAMEIT, a citizen of the United States, residing at Chicago, in the county of Cook and State of Illinois, have invented a new, original, and ornamental Design for an Article of Manufacture, of which the following is a specification, reference being had to the accompanying drawing, forming a part hereof.

The drawing is a front view of a badge or emblem, showing my new design.

I claim:

The ornamental design, as shown and described, for an article of manufacture.

MIECISLAS J. SZAMEIT.

Witnesses:

EDWARD S. SPIERINS,
CHARLES REMPERT.
